UNITED STATES PATENT OFFICE.

HERBERT S. HUMPHREY, OF KALAMAZOO, MICHIGAN, ASSIGNOR TO RUUD MANUFACTURING CO., OF PITTSBURGH, PENNSYLVANIA.

WATER HEATER.

Application filed November 6, 1922. Serial No. 599,271.

This invention relates to improvements in water heaters.

The main objects of the invention are:

First, to provide in a water heater of the coiled type an improved coupling and supporting means for the coils within the casing.

Second, to provide in a water heater an improved coupling member which greatly facilitates the assembling of the parts, avoiding the necessity for brazing and soldering.

Third, to provide an improved water heater structure in which the coils may be readily removed and replaced should occasion require.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a side elevation of a water heater embodying the features of my invention, the same being shown mainly in conventional form.

Fig. II is a vertical central section through the casing.

Fig. III is a detail view partially in horizontal section on a line corresponding to line 3—3 of Fig. II.

Fig. IV is a detail section on a line corresponding to line 4—4 of Fig. III.

Fig. V is a detail section on a line corresponding to line 5—5 of Fig. II.

In the drawing similar reference characters refer to similar parts throughout the several views and the sectional views are taken looking in the direction of the little arrows at the ends of the section lines.

Referring to the drawing, 1 represents the casing of the heater, 2 the base and 3 the top thereof. The top is provided with a vent flue 4. The burner is conventionally illustrated at 5. The heating coils 6 and 7 are disposed one within the other, the wind of the coils being opposite. These coils are connected to the water discharge and

supply pipes and are supported by the 55 couplings 8 and 9. The coupling 8 is provided with oppositely disposed arms 10 and 11 having coupling nuts 12 adapted to clamp the flange ends of the coils against the ends of the arms. This form of coupling being 60 old it is not detailed. The arms are disposed oppositely as stated and are of such length that one does not interfere with the manipulation of the coupling member of the other. The coupling member 8 is disposed through 65 an opening 13 provided therefor in the side of the casing near its lower end and has stop lugs 14 which are clamped against the inner side of the casing by means of the nut 15, the projecting end 16 of the coupling member being threaded to receive the nut and also the pipe coupling 17. Lugs 18 70 engaging recesses or notches 19 in the edge of the opening 13 support the coupling member 8 against rotative movement. The coupling member 9 is provided with arms 20 and 21 equipped with the coupling nuts 12, this coupling member being disposed through the hole 22 in the top of the casing and being provided with lugs 14 which are clamped against the inner side of the casing by the nut 15, lugs 18 being provided to prevent rotative movement of the coupling member. 75

The discharge pipe 23 is threaded upon 80 the projecting end of the coupling member.

With the parts thus arranged the coils are effectively supported as well as being connected to the supply and discharge pipes and should occasion require a coil may be 90 renewed or removed for cleaning should it become clogged.

The coils are connected to the couplings without the aid of brazing, as is general practice, and, in installing the heater all 95 that is required is to attach the pipes by means of the usual standard plumbing couplings or connections.

My improved couplings are very economical to produce and use of the same results 100 in a very decided economy in assembling in the heater and in attaching the heater to or installing in a house system.

Having thus described my invention, what I claim as new and desire to secure by Letters Patent, is:

1. In a water heater, the combination of a casing provided with a top and having a side

- opening near the bottom thereof and an opening in its top, spirally wound heating coils disposed one within the other, the wind of one coil being opposite that of the other, coupling and supporting members each having oppositely disposed arms connected to the ends of said coils, said arms being provided with couplings facilitating the connection of said coils thereto and being disposed so that 10 one arm does not interfere with the manipulation of the coil coupling of the other, said coupling members being disposed through said openings in said casing and provided with lugs limiting their outward movement 15 therein and supporting them against rotative movement in said openings, and nuts on the outer ends of said couplings clamping the same to said casing, the projecting ends of said coupling members being threaded at 20 the outside of said nuts to facilitate connection thereto.
2. In a water heater, the combination of a casing provided with a top and having a side opening near the bottom thereof and an opening in its top, spirally wound heating coils disposed one within the other, coupling and supporting members each having oppositely disposed arms connected to the ends of said coils, said arms being provided with couplings facilitating the connection of said coils thereto, said coupling members being clamped in said openings, their outer ends being adapted to receive pipe couplings. 3. In a water heater, the combination of a casing provided with a top and having a side opening near the bottom thereof and an opening in its top, spirally wound heating coils disposed one within the other, the wind of one coil being opposite that of the other, coupling and supporting members each having oppositely disposed arms provided with couplings engaging said coils, said coupling members being disposed through said openings in said casing and provided with lugs limiting their outward movement therein and supporting the coupling members against rotative movement in said openings, and nuts on the outer ends of said couplings clamping the same to said casing, the projecting ends of said coupling members being threaded at the outside of said nuts to facilitate connection thereto. 4. In a water heater, the combination of a casing, spirally wound heating coils disposed one within the other, coupling and supporting members each having oppositely disposed arms connected to the ends of said coils, said arms being provided with couplings facilitating the connection of said coils thereto, said coupling members being disposed through openings in said casing and being provided with lugs limiting their outward movement therein and supporting them against rotative movement, and nuts on the outer ends of said couplings clamping them to said casing, the ends of said coupling member projecting beyond the nuts to facilitate connection thereto. 5. In a water heater, the combination of a casing, spirally wound heating coils disposed one within the other, the wind of one coil being opposite that of the other, coupling and supporting members each having oppositely disposed arms connected to the ends of said coils, said arms being provided with couplings facilitating the connection of said coils thereto, said coupling members being clamped in the openings in said casing and projecting therefrom, the projecting ends being adapted to receive standard pipe couplings. 6. In a water heater, the combination of a casing provided with an opening, spirally wound heating coils disposed one within the other, the wind of one coil being opposite that of the other, a coupling and supporting member having oppositely disposed arms connected to said coils, said arms being provided with couplings facilitating the connection of said coils thereto and being disposed so that one arm does not interfere with the manipulation of the coil coupling of the other, said coupling member being disposed through said opening in said casing and provided with lugs limiting its outward movement and supporting it against rotative movement therein, and a nut on the outer end of said coupling clamping the same to said casing, the projecting end of said coupling member being threaded to facilitate connection thereto. 7. In a water heater, the combination of a casing provided with an opening, spirally wound heating coils disposed one within the other, the wind of one coil being opposite that of the other, a coupling and supporting member having oppositely disposed arms connected to said coils, said arms being provided with couplings facilitating the connection of said coils thereto and being disposed so that one arm does not interfere with the manipulation of the coil coupling of the other, said coupling member being clamped in said opening, and the projecting end of said coupling member being adapted to receive a pipe connection. 8. In a water heater, the combination of a casing provided with an opening, spirally wound heating coils disposed one within the other, a coupling, and supporting member having arms connected to said coils, said arms being provided with couplings facilitating the connection of said coils thereto, said coupling member being disposed through said opening in said casing and provided with lugs limiting its outward movement and supporting it against rotative movement therein, and a nut on the outer end of said coupling clamping the same to said casing, the projecting end of

said coupling member being threaded to facilitate connection thereto.

9. In a water heater, the combination of a casing provided with an opening, spirally wound heating coils disposed one within the other, and a coupling and supporting member having arms connected to said coils, said arms being provided with couplings facilitating the connection of said coils thereto,
10. said coupling member being clamped in said opening to project from the casing, the projecting end being adapted to receive a pipe coupling.

10. A coupling of the class described having oppositely disposed arms at one end provided with couplings facilitating the connection of pipes thereto, the other end of said coupling being threaded and provided with a clamping nut, and clamping and positioning lugs coating therewith, said coupling being threaded at the outside of the nut to facilitate the connection of a pipe thereto.

In witness whereof, I have hereunto set my hand and seal.

HERBERT S. HUMPHREY. [L.S.]
